AUDIO AMPLIFIER

George F. Genaust, Minneapolis, Minn.

Application March 9, 1955, Serial No. 493,131

2 Claims. (Cl. 179—171)

This invention has relation to audio amplifiers and concerns audio amplifiers capable of amplifying all frequencies and their harmonics encountered in speech, sounds and music without any apparent distortion.

In an amplifier made according to the present invention, the output is taken from a transformer, the primary of which is in the cathode circuit of the final stage of an amplifier. A screen grid of a vacuum tube of the previous stage is connected through this primary winding to the cathode of said final stage, a control grid of the final stage is tied directly to a plate of the preceding stage and a neon glow tube is connected between the cathode and the control grid in the final stage.

The figure of the drawing is a diagrammatic representation of an audio amplifier made according to the present invention.

Referring to the drawing and the numerals of reference thereon, an audio amplifier made according to the present invention includes a pentode 10, such, for example, as the vacuum tube designated 6SU6; a tube 11 connected to operate as a triode such, for example, as the tube designated 6V6; and a duo-diode 12 such, for example, as the tube designated 5Y3. The duo-diode 12, a power transformer 13, and a filter 14 constitute the power supply and supply the B-plus voltage to the amplifier along a wire 15. This part of the circuit forms no part of the present invention.

Audio input is fed to the circuit at terminals 16 and 17 from any suitable source (not shown). Terminal 17 is grounded and the two terminals 16 and 17 are connected across resistor 18. A control grid 19 of the pentode 10 is connected through an adjustable slider 20 to the resistor 18. Wire 15 is connected directly to a plate 21 of the triode 11 and through a resistor 22 to a plate 23 of the pentode 10.

A suppressor grid 24 and a cathode 25 of the pentode 10 are connected to each other and through a resistor 26 to ground. A control grid 27 of the triode 11 is directly connected to the plate 23 of the pentode 10. A primary winding 28 of an output transformer 29 is connected at one end to a cathode 30 of the triode 11 and at the other end to a resistor 31. The other end of this resistor 31 is connected to ground and a condenser 32 is connected across this resistor. A screen grid 33 of the pentode 10 is connected to said primary winding 28 of said output

transformer 29 at the point where the transformer winding is connected to the resistor 31.

A neon glow tube 34 is connected between the control grid 27 of the triode 11 and the cathode 30 of said triode.

5 In operation, the first or input stage including the pentode 10 is used as a Class A voltage amplifier with plate and screen voltages equal. The second or output stage including the triode 12 operates as a Class A power amplifier. This stage offers a very high impedance to 10 the input from the first stage and, therefore, has negligible loading effect on that stage. In this way, practically the entire voltage gain of the input stage is effectively utilized. The output transformer 29, in the cathode circuit of the triode 11 has a very low impedance and therefore there is practically no loss in power transfer in said transformer.

Screen grid 33 of the pentode 10, through its connection to primary winding 28 of output transformer 29, through the cathode 30 and the plate 21 of the triode 11 is maintained at the same voltage as is the plate 23 of the pentode.

20 Any variations in the supply voltage from the power supply are reflected back through the triode 11 and the primary winding 28 of the output transformer 29 to the screen grid 33 to keep this grid at the same potential as that of the plate 23 of the same tube. The amplified

25 signal is also fed back to the screen grid 33 of the pentode. This results in an output to the output transformer which has no audible hum or ripple from the power supply to mix with or modulate the amplified speech or music.

The neon glow tube 34, connected between the control grid 27 and the cathode 30 of the triode 11 serves to prevent arcing between said cathode and control grid until the triode warms up sufficiently to start conducting.

What is claimed is:

1. An audio amplifier including a power supply, a first 35 electronic tube having a first plate, a first cathode, a first control grid and a screen grid, a second electronic tube having a second plate, a second cathode and a second control grid, first, second and third resistors, an electrical connection between said power supply and said second plate, 40 an electrical connection including said first resistor between said power supply and said first plate, an electrical connection between said first plate and said second control grid, first and second input terminals, an electrical connection between said first input terminal and said first control grid, an output transformer, an electrical connection between said second cathode and a first end of one coil of said output transformer, an electrical connection between a second end of said coil of said transformer and the first end of said second resistor and said screen 45 grid, an electrical connection between said first cathode and a first end of said third resistor, a capacitor connected across said second resistor, and a common electrical connection between said power supply, said second input terminal, a second end of said second resistor and a 50 second end of said third resistor.

2. The combination as specified in claim 1 and a glow discharge tube connected between said second control grid and said second cathode.
